US00D595907S

(12) **United States Design Patent**
Rutherford et al.

(10) **Patent No.:** **US D595,907 S**
(45) **Date of Patent:** **** Jul. 7, 2009**

(54) **BIRDCAGE ATTACHMENT**

(75) Inventors: **Ryan Rutherford**, Rutherford, NJ (US);
Klaus Woltmann, Demarest, NJ (US);
Jonathan Willinger, Tenafly, NJ (US)

(73) Assignee: **J.W. Pet Company, Inc.**, Teterboro, NJ
(US)

(**) Term: **14 Years**

(21) Appl. No.: **29/306,985**

(22) Filed: **Apr. 21, 2008**

Related U.S. Application Data

(60) Division of application No. 29/266,259, filed on Sep. 15, 2006, now Pat. No. Des. 586,957, which is a continuation-in-part of application No. 29/264,790,

(57) **CLAIM**

We claim the ornamental design for a birdcage attachment, as shown and described.

DESCRIPTION

FIG. 1 is a perspective view of a birdcage attachment;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the designs that are shown in broken lines do not form part of the claimed design.

1 Claim, 7 Drawing Sheets

Related U.S. Application Data

filed on Aug. 17, 2006, now Pat. No. Des. 554,298, which is a division of application No. 29/230,071, filed on May 16, 2005, now Pat. No. Des. 530,866, which is a division of application No. 29/180,987, filed on May 2, 2003, now Pat. No. Des. 508,589, which is a continuation-in-part of application No. 10/371,646, filed on Feb. 21, 2003, now Pat. No. 6,971,332, application No. 29/266,259, which is a continuation-in-part of application No. 29/230,071, filed on May 16, 2005, now Pat. No. Des. 530,866, which is a continuation-in-part of application No. 11/245,556, filed on Oct. 7, 2005, now abandoned, which is a continuation-in-part of application No. 29/230,071, filed on May 16, 2005, now Pat. No. Des. 530,866, and a continuation-in-part of application No. 11/182,380, filed on Jul. 15, 2003, now abandoned, which is a continuation of application No. 10/371,646, filed on Feb. 21, 2003, now Pat. No. 6,971,332.
